L. T. ROBINSON ET AL

VAPOR ELECTRIC DEVICE

Filed Nov. 19, 1925

UNITED STATES PATENT OFFICE.

LEWIS T. ROBINSON AND CAMILLE A. SABBATH, OF SCHENECTADY, NEW YORK, AS
SIGNORS TO GENERAL ELECTRIC COMPANY, A CORPORATION OF NEW YORK.

VAPOR ELECTRIC DEVICE.

Application filed November 19, 1925. Serial No. 70,201.

Our invention relates to vapor electric devices wherein current is transmitted between a cathode and an anode alternately charged to positive and negative polarities, and has 5 for its principal object the provision of a method and means for preventing the transmission of inverse current through the anode when it is charged to a negative potential.

In the operation of vapor electric devices, 10 such as the mercury rectifier, current is transmitted between a positively charged anode and the cathode through an electric arc which carries a multitude of positive ions. The presence of positive ions in the vicinity 15 of the anode is desirable when it is positively charged and is transmitting current because these ions reduce space charge and facilitate the transmission of current through the device. When the anode is charged to a negative 20 polarity and is not transmitting current, however, the presence of positive ions in the vicinity of the anode is undesirable for the reason that they are attracted to the anode and tend to raise its temperature to a point 25 at which electrons are emitted. These electrons ionize the surrounding vapor, thus producing more positive ions and establishing a condition likely to lead to the formation 30 of destructive arcs, commonly denoted by the expression "arc back," between the negatively charged anode and some other part of the device.

It is customary to surround the anodes 35 of a vapor electric device with a shield or baffle for protecting them from the positive ions of the arc when they are not transmitting current. With this construction, trouble is encountered due to the presence of positive ions within the anode shield or 40 baffle at the instant the anode polarity is changed from a positive to a negative value. In accordance with our invention, this difficulty is avoided by the provision of means for attracting the positive ions away from 45 the negatively charged anode and for intercepting the electrons emitted from the anode before they have had an appreciable effect on the surrounding vapor.

Our invention will be better understood 50 from the following description when considered in connection with the accompanying drawings and its scope will be pointed out in the appended claims.

Referring to the drawings, Fig. 1 shows 55 a fragmentary sectional view of a mercury

rectifier wherein my invention has been embodied; Figs. 2 and 3 show various details thereof; Fig. 4 is a sector diagram showing the phase relation between the anode, shield and control electrode voltages; and Figs. 5 60 and 6 relate to a modified form of mercury rectifier.

Figs. 1, 2 and 3 show a mercury rectifier 65 wherein current from a suitable source is transmitted through an arc between an anode 1 and a cathode 2 which is located in a container 3 and is supported by an insulated wall portion 4 of this container. Chambers 5 and 6 are provided for circulating 70 a cooling medium in contact with the container walls. It will be observed that an insulation member 7 is arranged to form a seal between the anode 1 and the cover of the container 3 upon which it is supported, that a control electrode 8 and an anode shield 9 are supported by an insulator 10 extending between the anode and the tank cover, that a pipe 11 is provided for applying a cooling 75 medium to the anode 1, that the anode 1 is connected to a lead 12 through a primary winding 13 of an induction device comprising an adjustable core member 15 and a secondary winding 16, that control electrode 8 is connected to the anode 1 through a resistor 17 and the secondary 80 winding 16, and that the shield 9 is insulated from the control electrode 8 by insulation member 10 and is connected to the control electrode 8 through an adjustable condenser 18 which is connected to the secondary circuit 16 in series with a resistor 19. It will be readily understood that, 85 while only one anode appears in the figure, the rectifier will usually comprise either a pair of electrodes connected to the opposite terminals of a single phase source or a plurality of anodes connected to a polyphase source in any suitable manner.

With the connections illustrated, the phase 90 relation between the voltages of the anode 1 and the control electrode 8 is dependent on the adjustment of the movable core member 15 of reactance device 14, and the phase relation between the voltages of control electrode 8 and shield 9 is determined by adjustment of condenser 18. Assuming the vectors 1', 8' and 9' of Fig. 4 to represent the voltages of anode 1, control electrode 8 and shield 9 respectively, it will be seen that 95 the control electrode voltage leads both the 100 control electrode and the shield. The 105 control electrode voltage leads the anode voltage by an angle which is dependent on the 110 adjustment of condenser 18.

anode and shield voltages and is somewhat larger than the anode voltage due to the fact that it is connected to the anode through the secondary winding 16 which raises the 5 control electrode voltage above that of the anode by an amount dependent on the magnitude of the current transmitted through the anode.

The manner in which the phase relation 10 between the anode, control electrode and shield voltages is utilized to prevent arc back due to the presence of positive ions within the shield when the anode assumes a negative polarity will be explained on the assumption 15 that transmission of current between the anode and cathode has ceased and the anode has just assumed a negative polarity. Under these conditions, the shield is charged to a negative value somewhat greater than that 20 of the anode, the polarity of the control electrode is still positive and the positive ions are largely prevented from reaching the anode both due to the positively charged control electrode which repels them and to the 25 comparatively large negatively charged surface of the shield which attracts them. Arc back due to the residual positive ions is thus prevented.

As previously indicated, arc back is also 30 likely to be produced by the ionization of the surrounding vapor due to the emission of electrons from the negatively charged anode. This difficulty is most pronounced when the anode is operated at a high temperature and 35 is charged to a comparatively high negative voltage. Referring to the vector diagram of Fig. 4, it will be noted that the control electrode assumes a negative potential soon after the polarity of the anode is changed from a 40 positive to a negative. The interval of time between the changes in the polarities of the anode and control electrode may be controlled by the inductance device 14 and should be just sufficient to allow deionization 45 of the vapor within the shield. With proper adjustment of the reactance device 14, a negative voltage is applied to the control electrode while the negative voltage of the anode is comparatively small and the emission of 50 electrons from the anode is retarded in a manner to prevent ionization and arc back. The control electrode thus performs the double function of protecting the anode from the positive ions during deionization and of 55 preventing ionization of the vapor by electrons emitted from the anode when it is charged to a comparatively high negative voltage.

Fig. 5 is a diagrammatic showing of a system 60 wherein current supplied from a suitable alternating current source is transmitted to a direct current circuit 20 through a polyphase transformer 21 comprising secondary windings 22, 23 and 24, a rectifier comprising anode 25 and cathode 26, an interphase

transformer 27 of well known construction, and a reactor 28 which is provided for smoothing out pulsations in the current of the circuit 20. It will of course be understood that, while only one anode 25 has been 70 illustrated, the rectifier will comprise a plurality of anodes each connected to a different secondary terminal of the transformer. A spiral grid or control electrode 32 is interposed between the anode 25 and cathode 26 75 and is connected to the anode through the resistor 17 and a phase control device 28 supplied with current from the left hand part of the secondary winding 22 through a potential transformer 29. As indicated by Fig. 6, the active surface of the anode 25 is located within a funnel-shaped baffle to which it is connected through a resistor 31. The resistor 31 corresponds to the resistor 19 of Fig. 1 and may be connected between the 80 anode and shield either independently of the phase control device or in series therewith as previously explained.

The form of anode shield illustrated by Fig. 6 has the advantage that it radiates heat 90 away from the anode to the cool wall of the container and allows the vapor surrounding the anode to readily expand toward the container wall thus preventing excessive rise in temperature and vapor pressure around the 95 anode. The operation of the modification shown by Figs. 5 and 6 will be apparent in view of the previous discussion of Figs. 1 to 4.

The embodiments of the invention illustrated and described herein have been selected for the purpose of clearly setting forth the principles involved. It will be apparent, however, that the invention is susceptible of being modified to meet the different conditions encountered in its use and we therefore aim to cover by the appended claims all modifications within the true spirit and scope of our invention.

What we claim as new and desire to secure by Letters Patent of the United States, is:—

1. The method of operating a vapor electric device comprising a control electrode interposed between an anode and an anode shield, which comprises changing the polarity of said shield and anode, and thereafter changing the polarity of said control electrode.

2. The method of operating a vapor electric device comprising a control electrode interposed between an anode and an anode shield, which comprises successively changing the polarities of said shield, said anode and said control electrode.

3. A vapor electric device wherein current is transmitted through an arc between a cathode and an anode alternately charged to positive and negative polarities, comprising an arc shield for protecting said anode when 130

- it is charged to a negative polarity, a control electrode interposed between said shield and anode, means for applying voltages to said shield and control electrode, and means for controlling the relation between the voltage of said anode and the voltages of said shield and control electrode.
4. A vapor electric device wherein current is transmitted through an arc between a cathode and an anode alternately charged to positive and negative polarities, comprising an arc shield for protecting said anode when it is charged to a negative polarity, a control electrode interposed between said shield and anode, means for applying voltages to said shield and control electrode, and means for controlling the phase relation between the voltages of said shield and control electrode.
5. A vapor electric device comprising an external anode, an anode shield insulated from said anode, and a control electrode interposed between said anode and shield and insulated therefrom.
6. A vapor electric device comprising an external anode, an anode shield insulated from said anode, a control electrode interposed between said anode and shield and insulated therefrom, and means for applying a cooling medium to the external surface of said anode.
7. A vapor electric device comprising an external anode, an anode shield insulated from said anode, a control electrode interposed between said anode and shield and insulated therefrom, and means for applying potentials of predetermined magnitude and phase relation to said anode, control electrode and shield.
8. The method of operating a vapor electric device comprising a control electrode interposed between an anode and an anode shield, which comprises applying a negative potential to said anode and maintaining a positive potential at said control electrode during deionization of the vapor enclosed within said shield.
9. The method of operating a vapor electric device comprising a control electrode interposed between an anode and an anode shield, which comprises applying a negative potential to said anode, applying a positive potential at said control electrode during deionization of the vapor within said shield, and changing the polarity of said control electrode at a predetermined time after said anode has been charged to a negative potential.

In witness whereof, we have hereunto set our hands.

LEWIS T. ROBINSON.
CAMILLE A. SABBAH.
